AUTOMATIC TRAIN STOP SYSTEM

Gilbert C. Whitney, New York, N. Y.

Application July 6, 1933, Serial No. 679,174

11 Claims. (Cl. 246—49)

This invention relates in general to automatic train stop systems and automatic block signal systems for railroads and more particularly, though not exclusively, to novel means for controlling the automatic train stop associated with an automatic block signal when said block signal is displaying a restrictive indication and is applicable whether the block signal system is operated or controlled electrically or electro-pneumatically and whether the train stop system is operated or controlled electrically or electro-pneumatically and is also applicable whether co-action between the train stop system and a train is carried into effect mechanically or electrically.

15 The established practice in the art of railway signalling and train control for rapid transit railroads in particular is to provide an automatic block signal system adapted to convey information, in the form of colored light, to the operator of an approaching train, as to the occupancy or non-occupancy of the track in the advance territory. Associated with each block signal there is provided an automatic train stop mechanism to stop the passage of a train, by causing application of the train brakes, in the event that a train attempts to pass a signal when such signal is displaying a stop indication. Both the signal and train stop mechanism are controlled by track circuits. In all of these systems the train stop mechanism assumes the non-stopping position when the signal indicates caution or proceed. In one of these systems the train stop mechanism assumes the stopping position immediately after the train passes it. In another 30 of these systems the train stop mechanism remains in the non-stopping position until the rear end of the train has passed an appreciable distance by it and this even though the signal may be indicating stop. In both of these systems means are provided to enable the train operator to put the train stop mechanism in a non-stopping position when the signal indicates stop—in the first mentioned system the means includes a key to be actuated by the train operator and in the second mentioned system the effect is produced by arranging the track circuit, the signal, and the train stop mechanism in a definite order. Both of these systems may be arranged further to prevent the signal from displaying a caution or proceed indication unless and until after the associated train stop has assumed the stopping position after the passing of a train. The object sought is to prevent rear end collisions. This object is attained only in the first mentioned system and at the cost of the time neces-

sary to operate the key and this means loss of track capacity. In the second mentioned system the object sought is attained only in part because of the delay in the train stop mechanism assuming the stopping position and this 5 means reduced protection to trains. Furthermore, the required definite order of arrangement in the second mentioned system leads to high installation costs because subway and elevated structures must be modified and expensive additional equipment must be installed to obtain curve protection. And, again, the definite order of arrangement required by the second mentioned system, at times, prevents the normal functioning of the signaling system and thereby causes 10 loss in track capacity.

The objects of my invention, as hereinafter disclosed, are (1) to provide a system in which the automatic train stop mechanism assumes the stopping position immediately after the rear end of the train has passed it; (2) to provide a system permitting train operation of the train stop mechanism and thereby avoid need for key operation; (3) to provide a system to insure that a train stop mechanism in the rear of the train 20 is in the stopping position to protect said train when a train stop mechanism is to be put in the non-stopping position by a train; (4) to carry the objects of this invention into execution with a minimum of definite order of arrangement and apparatus and therefore at a minimum cost; and (5) to avoid interference with the regular operation 25 of the block signal system.

In describing this invention in detail, reference will be made to the accompanying drawings consisting of Figs. 1 to 4; showing diagrammatically the broad novelty of this invention in its simple fundamental form in Fig. 1 in a manner to make it easy to understand the invention rather than with the idea of showing any preferred embodiment and in Figs. 2 and 3 are shown variations in detail in carrying the invention into practice and in Fig. 4 I have shown an automatic block signal system combined with this invention. Similar reference characters are used to 30 represent similar parts in all of the figures.

Referring now to Fig. 1; there is shown a stretch of railroad track including track rails 5 and 6 electrically separated into track sections A, B, and C by insulated track rail joints 7 to 50 permit the working of a track circuit in the usual manner. The track rails of each section A, B, and C are included as a part of the well-known normally closed track circuit—sec. C having a source of energy 8 and a track relay 9 (referred 55

to in the claims and elsewhere in the specification as the second track circuit)—sec. B having a source of energy 3 and track relay 18 (referred to in the claims and elsewhere in the specification as the first track circuit)—sec. A is similarly equipped but not illustrated because it is not necessary to a clear understanding of this invention. The functioning of these track circuits is well understood in the art and need not be described other than to state that, in regular track circuit operation, certain contacts operated by the track relay are closed only when the track section is not occupied by a train and these contacts are termed front contacts and certain contacts operated by the track relay are closed only when the track section is occupied by a train and these contacts are termed back contacts.

For each track section I provide an automatic train stop mechanism situated at a selected point along the wayside and arranged to co-act, mechanically, electrically, or otherwise as the case may be, with train carried apparatus to cause application of the train brakes when said wayside train stop mechanism is in the stopping position and a train attempts to pass it but which train stop mechanism will not cause application of the train brakes when said train stop mechanism is in the non-stopping position. The point selected for the location of these wayside train stop mechanisms 11 (for sec. C) and 12 (for sec. B) is located at a distance X from the beginning of the respective track section to allow time for a slow operating train stop mechanism to assume the nonstopping position and thereby control the speed of a train at this point by requiring the lapse of a predetermined time interval while the front end of the train is passing over said distance X.

Distance X will not be longer than the distance between the front co-acting train carried apparatus and the rear wheels of the shortest train operated.

The operating mechanism 13 for train stop 11 cannot operate instantly in operating train stop 11 from the stopping position to the non-stopping position and this inherent time for operation is taken into consideration in determining distance X. This inherent time for operation is substantially constant for mechanisms of the same kind but different as between different kinds. These train stop mechanisms are arranged, by means of counterweights, compression springs, or the like, for the mechanical type, to assume the stopping position where the train stop arm 11 will co-act with train carried apparatus to cause application of the train brakes in the event that a train attempts to pass when train stop 11 is in the stopping position. The train stop and operating mechanisms always assume said stopping position when they are not controlled to the non-stopping position.

As illustrated in the drawings all wayside train stops are located on the same side of the track but it is to be understood that said wayside train stops may be located on either or both sides of the track and arranged to co-act, when in the stopping position, with the train carried apparatus.

The co-acting train carried apparatus may be located on either or both sides of the train, in front of the train truck or in the rear of the train truck, and at the front end of the train or at the rear end of the train, as desired.

Solely in the interest of simplicity the source

of energy for other than the track circuits is not shown in the figures, but it is to be understood that a suitable source or sources of energy is provided and represented by the characters B and O for the terminals of such a source of energy and 5 which may be direct or alternating current.

Train stop operating mechanism 13 for train stop 11 is controlled by a circuit which may be traced as follows: from B to contact 14, closed only when train stop 12 is in the stopping position, wire 15, track relay contact 16 closed only when sec. B is occupied by a train, wire 17, track relay contact 18 closed only when sec. C is occupied by a train, wire 19, to operating mechanism 13 to O. When this circuit is complete, that is, 15 all contacts are closed, operating mechanism 13 will be energized and train stop 11 will assume the non-stopping position. When this circuit is not complete, due to any of the contacts being open, train stop 11 will be in the stopping position. Fig. 1 shows train stops 11 and 12 in the stopping position. The train stop operating mechanism for train stop 12 is similarly controlled.

Distance Y is determined solely by the condition that contact 14 on train stop 12, closed only in the stopping position of 12, is used in the control circuit of train stop operating mechanism 13 for train stop 11. Therefore distance Y will be such as to permit of train stop 12 being in 30 the stopping position before the front end of a train enters sec. C. When the approach block (sec. B) is shorter than the longest train operated on the railroad contact 14 is located on a train stop farther in the rear.

In order that the train operator may know the location and position of train stop 11 I provide visual indication in the form of two distinctly differently colored lamps at each train stop. One of these lamps, preferably red in color, is controlled by a circuit which may be traced as follows: from B to contact 20, closed only when train stop 11 is in the stopping position, wire 21, lamp 22, to O. The other of these lamps, preferably of color white, yellow, or green, is controlled by a circuit which may be traced as follows: from B to contact 23, closed only when train stop 11 is in the non-stopping position, wire 24, lamp 25, to O.

In proceeding over the track in the direction of 50 the arrow the front end of the train enters sec. B and continues on to enter sec. C. When the train enters sec. B, contact 16 closes and when the front end of said train enters sec. C, contact 18 closes. When the rear end of said train passes 55 out of sec. A, (before the front end reaches sec. C) train stop 12 assumes the stopping position to stop a following train. The control circuit for operating mechanism 13 is now complete. Train stop 11 assumes the non-stopping position and 60 the associated lamp indication changes accordingly to inform the train operator. When the rear end of said train passes out of sec. B, contact 16 on track relay 18 opens the control circuit for 65 13; train stop 11 assumes the stopping position; and the visual lamp indication changes accordingly.

As pointed out hereinbefore distance X is determined by the inherent time required for operation of the train stop operating mechanism 13 70 and this time interval is taken into consideration in enforcing a predetermined train speed. For example, if mechanism 13 requires 2 seconds for operation and the selected train speed to be enforced is 5 miles per hour, then distance X 75

will be 15 feet, because a train speed of 5 miles per hour is equal, approximately, to 7.5 feet per second. Again, if the inherent time for said operation is 2 seconds and the allowable train speed is 10 miles per hour, then distance X will be 30 feet, and so on. But, if the inherent operation time of 13 is 5 second and the allowable train speed is 5 miles per hour, then distance X will be 3.75 feet. In actual railroad operation it is not practicable to operate a train with distance X as short as 3.75 feet. I provide for this condition by including a time delay device, fixed or adjustable as desired, in the control circuit of the train stop operating mechanism 13.

With the inclusion of a time delay means a definite distance X is no longer necessary and any distance X suited to practical railroad construction and operation may be used and the train speed will be restricted by the time delay factor as will be explained hereinafter.

Referring now to Fig. 2; Fig. 2 is similar to Fig. 1 in all respects except that a time delay device 26 has been included in the control circuit of mechanism 13 to lengthen the time of operation and contact 14 of Fig. 1 is not included. Time delay device 26 is of the slow pick up type of relay with fixed or adjustable time factor as desired. This type of relay does not close its front contact 27 to wire 28 until after the lapse of the established interval of time after said relay 26 has been energized and which opens contact 35 (Fig. 3) from wire 36 practically simultaneously with the closing of contact 27 to wire 28, and which opens said contact 27 from wire 28 and closes said contact 35 to wire 36 immediately when said relay 26 is deenergized. Device 26 is controlled by a circuit which may be traced as follows: from B to track relay contact 16, wire 17, track relay contact 18, wire 19, to device 26, to O. Mechanism 13 is controlled by a circuit which may be traced as follows: from B to contact 27, closed only after the lapse of the established time interval after the control circuit for device 26 has been completed, wire 28, to operating mechanism 13 to O.

Referring to Fig. 2;—the operation is as follows: In proceeding over the track in the direction of the arrow the front end of the train enters sec. B and continues on to enter sec. C. When the train enters sec. B, contact 16 closes and when the front end of said train enters sec. C, contact 18 closes. The control circuit for 26 is now complete. After the lapse of the established time interval contact 27 closes. The control circuit for mechanism 13 is now complete. Therefore, train stop 11 assumes the non-stopping position and the visual indication changes accordingly to inform the train operator. When the rear end of said train passes out of sec. B, contact 16 opens to open the control circuit of device 26. When the control circuit of 26 opens, contact 27 opens immediately. The control circuit of 13 is now open. Therefore, train stop 11 assumes the stopping position with appropriate change in the visual indication as before. Fig. 2 shows train stop 11 in the stopping position.

In Figs. 1 and 2, the system illustrated and described may be termed "normal danger" from the fact that the automatic train stop is always in the stopping position except when it assumes the non-stopping position to permit the passing of a train at a predetermined speed. When there is no train in the advance territory it is desirable that the train proceed at a higher speed, and this requires that means be provided

so that the train stop may assume the non-stopping position whenever the territory in advance of the train stop 11 is not occupied by a train, but, which will retain the advantages hereinbefore explained in connection with Fig. 2.

In Fig. 3 such a system, known as "normal clear" is illustrated and the system of Fig. 2 is incorporated therein.

Referring now to Fig. 3; there is shown a stretch of track divided into track sections A, 10 B, and C, and an additional track section D has been shown. Sec. D is provided with source of energy 8 and track relay 29 and is referred to in the claims and elsewhere in the specification as the third track circuit. The normal clearing 15 circuit for train stop 11 may be traced as follows: from B to front contact 31 on track relay 29, to wire 32, to front contact 33 on track relay 9, to wire 34, to wire 30, to operating mechanism 13, to O. There is also provided a normal re- 20 taining circuit for train stop 11 and this circuit may be traced as follows: from B to contact 16 on track relay 10, to wire 41, to wire 17, to back contact 35 on device 26, to wire 36, to back contact 37 on track relay 9, to wire 38, to contact 25 39 on operating mechanism 13 and closed only when train stop 11 is in the non-stopping position, to wire 30, to operating mechanism 13, to O. The normal clearing circuit for train stop 12 may be traced as follows: from B to front contact 30 40 40 on track relay 9, to wire 36, to back contact 35 on device 26, to wire 17, to front contact 41 on track relay 10, to wire 42, to wire 43, to operating mechanism 13a for train stop 12, to O. It will be observed that the normal clearing circuit 35 for train stop operating mechanism 13a for train stop 12, in part also serves for the normal retaining circuit for train stop operating mechanism 13 for train stop 11. When either the normal clearing circuit or the normal retaining 45 circuit is complete the respective train stop will assume or be retained in the non-stopping position. Except for the inclusion of contact 35 in the circuit which serves in part as the normal clearing circuit for mechanism 13a, hereinbefore traced, and which serves in part as the normal retaining circuit for mechanism 13, hereinbefore traced, for checking purpose and to permit the incorporation of my invention, this normal clearing circuit and normal retaining circuit is old 50 and well understood in the art.

My invention as incorporated in Fig. 3 is the same as shown and described in connection with Fig. 2. Because of the fact that the character reference for the control circuit of device 26 is different said circuit is traced in Fig. 3 as follows: from B to contact 16 closed only when sec. B is occupied by a train, to wire 41, to wire 17, to wire 17a, to contact 18 closed only when sec. C is occupied by a train, to wire 19, to device 26, to O. The circuit for the control of mechanism 13 via device 26 is traced as follows: from B to contact 27 closed only after the lapse of the established interval of time after the control circuit for device 26 has been completed, wire 28, to wire 30, to mechanism 13, to O. As explained hereinbefore contact 27 does not close until the lapse of the established time interval after the control circuit for device 26 is complete and that contact 27 opens immediately when the control circuit for 26 opens. As hereinbefore pointed out, contact 35 controlled by device 26 remains closed until the lapse of said established time interval after the control circuit for device 26 is complete, and contact 35 closes immediately when the control 75

circuit for 26 opens. In Fig. 3 the visual indication scheme is the same as in Figs. 1 and 2 and in connection therewith it should be noted that the circuit including contact 23 is complete indicating that train stop 11 is in the non-stopping position. Fig. 3 shows train stops 11 and 12 in the non-stopping position.

The circuit and contacts which control time delay means device 26, hereinbefore described, and the control of mechanism 13 by said time delay means, device 26, hereinbefore described, provide an auxiliary means for operating train stop 11 from the stopping position to the non-stopping position and is referred to as auxiliary means hereinafter and in the claims.

The purpose of incorporating my invention in a normal clear train stop system, as in Fig. 3, is to provide a means whereby a following train may pass, at restricted speed, train stop 11 before the rear end of a leading train has passed out of sec.

D. The operation is explained hereinafter.

Referring to Fig. 3; as shown, the track, consisting of secs. A, B, C, and D, is not occupied, the track relay front contacts are closed, train stop 11 is in the non-stopping position, and the visual indication, to inform a train operator, in sec. B, that he may proceed at speed, is displayed at train stop 11. In proceeding over the track in the direction of the arrow the train enters sec. B and continues on to enter secs. C and D. The normal clearing circuit for mechanism 13, hereinbefore described, remains complete until the train enters sec. C. The normal retaining circuit for mechanism 13, hereinbefore traced, is completed at the time the train enters sec. C, by the closing of contact 16 on track relay 10 (closed when the train entered sec. B) and contact 37 on track relay 9 closed when the train entered sec. C. Therefore, while the train is occupying secs. B and C, train stop 11 is retained in the non-stopping position. When the rear end of said train passes out of sec. B, the normal retaining circuit is opened at contact 16 and train stop 11 assumes the stopping position with appropriate change in the visual indication. Train stop 11 now remains in the stopping position until the rear end of said train passes out of sec. D (at which time the normal clearing circuit is reestablished) unless said train stop 11 be put in the non-stopping position by a following train in a manner now to be described. Assume that the first train stopped with its rear end occupying sec. D. Train stop 11 is in the stopping position because the normal clearing circuit is open at contact 31 and the normal retaining circuit is open at contacts 16, 37, and 39. A following train enters sec. B and continues on to enter sec. C. At the time said following train enters sec. B, contact 16 on track relay 10 closes and at the time said following train enters sec. C, contact 18 on track relay 9 closes and thus the circuit for the control of time delay device 26 from B, contact 16, wire 17, wire 17a, contact 18, wire 19, to device 26, to O, is completed. After the lapse of the established time interval of device 26, contact 27 on device 26 closes to complete a circuit from B, to contact 27 (now closed), to wire 28, to wire 30, to mechanism 13, to O, whereupon train stop 11 is operated to the non-stopping position and said following train may pass. The purpose of time delay device 26 and control circuit therefor and the control of train stop 11 by said device 26 is to provide a means whereby train stop 11 may be operated to the non-stopping position independently of the normal clearing circuit. In view of the fact that the established

time interval for device 26 does not start until after contact 18 closes (due to said following train entering sec. C) and that contact 27 does not close, to complete the circuit to mechanism 13, until at the end of said time interval, it is evident that said train stop 11 will remain in the stopping position until after the established time interval after said following train enters sec. C (closing of contact 18). The control of mechanism 13 by time delay device 26, therefore, provides means whereby the speed of a moving train is restricted to a predetermined speed while passing over distance X, while the normal clearing circuit of mechanism 13 is not complete. It is manifest that the brakes of said following train will be applied by train stop 11 in the event that the established time interval for device 26 has not elapsed before said train reaches said train stop 11. When the rear end of said following train passes out of sec. B train stop 11 assumes the stopping position, and so on. As explained hereinbefore, mechanism 13 does not operate instantaneously; therefore, the opening of contact 35 in the normal retaining circuit is followed sufficiently soon by the closing of contact 27 to prevent train stop 11 assuming the stopping position under these circumstances.

The economic operation of a railroad requires that trains be operated at varying speeds according as more or less of the track in the advance territory is or is not occupied by a train and the means used to inform the train operator consists of a block signal system controlled automatically by track circuits. Such a system incorporating my invention is shown in Fig. 4.

Referring to Fig. 4; there is shown a stretch of track divided into track sections A, B, C, D, and E, which are equipped with track circuits in the usual manner as hereinbefore explained. At the entrance to each track section there is shown a block signal suitably equipped with R (red), Y (yellow), and G (green) lamps and arranged to inform the train operator whether the train should stop, proceed with caution, or proceed at speed, respectively. In general the lighting of these signal lamps is selectively controlled so that only one lamp at a block signal is lighted at any given time and this condition is obtained by means of a system of circuits controlled by track circuits and in turn controlling the lamp circuits. The means involved to obtain the selective control of the R, Y, and G lamps includes an H relay and control circuit therefor and a D relay and control circuit therefor. The circuit for the H relay for the signal at the entrance to sec. C may be traced as follows; from B to contact 31 on track relay 29, to wire 32, to contact 33 on track relay 9, to wire 34, to H relay, to O. When this circuit is complete only the front contacts controlled by this H relay are closed and when this circuit is not complete only the back contacts controlled by this H relay will be closed. The circuit for the D relay for the signal at the entrance to sec. C may be traced as follows; from B to contact 44 controlled by the H relay of the signal in advance (that is, located at the entrance to sec. D), to wire 45, to contact 46 on H relay for the signal at the entrance to sec. C, to wire 47 to D relay, to O. When this circuit is complete only the front contacts controlled by this D relay will be closed and when this circuit is not complete only the back contacts controlled by this D relay will be closed. The circuit for R lamp may be traced as follows; from B to contact 48 on H relay, to wire 49, to R lamp, to O. Only when this circuit is complete will R lamp

be lighted. The circuit for the Y lamp may be traced as follows; from B to contact 50, to wire 51, to contact 52 on D relay, to wire 53, to contact 54 on H relay, to wire 55, to Y lamp, to O. Only when this circuit is complete will Y lamp be lighted. The circuit for G lamp may be traced as follows; from B to contact 50, to wire 51, to contact 52 on D relay, to wire 56, to G lamp, to O. Only when this circuit is completed will G lamp be lighted.

Still referring to Fig. 4; the normal clearing circuit for train stop 11 may be traced as follows; from B to contact 48 on H relay, to wire 30, to mechanism 13, to O. The normal retaining circuit for train stop 11 may be traced as follows; from B to contact 16 on track relay 10, to wire a17, to wire 17, to contact 37 on track relay 9, to wire 38, to contact 39 on operating mechanism 13, closed only when train stop 11 is in the non-stopping position, to wire 30, to operating mechanism 13, to O.

My invention as incorporated in Fig. 4 includes the control of mechanism 13 by the auxiliary means including time delay means device 26. The control circuit of device 26 may be traced as follows: from B to contact 16 closed only when sec. B is occupied by a train, to wire a17, to wire 17, to wire b17, to contact 14 closed only when train stop 12 is in the stopping position, to wire 17a, to contact 18 closed only when sec. C is occupied by a train, to wire 19, to device 26, to O. The circuit for the control of mechanism 13 via device 26 is the same as described hereinbefore in connection with Fig. 3, and is as follows: from B to contact 27 closed only after the lapse of the established time interval after the control circuit for device 26 has been completed, to wire 28, to wire 30, to mechanism 13, to O.

The functioning of device 26 is the same as explained, hereinbefore, in connection with Figs. 2 and 3, and it is believed unnecessary to repeat it here.

The incorporation of my invention in an automatic block signal controlled train stop system, as in Fig. 4, is to provide a means to operate train stop 11 to the non-stopping position so that a train may pass, at restricted speed, an automatic block signal which is displaying a stop (R) signal or other restrictive signal indication.

As explained, hereinbefore, in connection with Fig. 1, distance Y is determined solely by the condition that contact 14 on train stop 12 closed only in the stopping position of train stop 12, is included in the control circuit of time delay means device 26. When the approach block (sec. B) is shorter than the longest train operated on the railroad contact 14 is located on a train stop farther in the rear.

The circuit for the H relay for the signal located at the entrance to sec. B may be traced as follows; from B to contact 40 on track relay 9, to wire 17, to contact 41 on track relay 10, to wire 42, to H relay, to O. It will be observed that the circuit for the H relay for the signal located at the entrance to sec. B, in part, serves also for the normal retaining circuit for train stop operating mechanism 13 for train stop 11.

The block signal system portrayed in Fig. 4 in general is old and well understood in the art and is illustrated only to show the incorporation of my invention in a block signal system.

Checking contact 35 on device 26 is now included in the D relay control circuit for the signal located at the entrance to sec. B and this circuit may be traced as follows; from B to contact 57

on H relay for the signal at the entrance to sec. C, to wire 58, to contact 35 on device 26, to wire 59, to contact 60 on H relay for the signal at the entrance to sec. B, to wire 61, to D relay, to O.

The functioning of the visual lamp indication 5 is the same as explained in connection with Figs. 1, 2, and 3, and it is believed unnecessary to repeat it here. Lamp 22 and control circuit of Figs. 1, 2, and 3 is not included in Fig. 4 because the R lamp of the block signal serves the same 10 purpose.

Distances X and Y are determined entirely on the same basis as has been explained hereinbefore in connection with Fig. 1 and it is believed unnecessary to repeat it here.

Secs. A, B, C, D, and E and so on are similarly equipped.

As shown in Fig. 4, secs. A, B, C, D, and E are unoccupied, the train stops 11 and 12 are in the non-stopping position, and at all block signals 20 the G lamps are lighted to inform a train operator that the train may proceed. In proceeding over the track in the direction of the arrow the train enters sec. B and continues on to enter secs. C, D, and E. When the front end of the train enters 25 sec. C, block signal lamp G at the entrance end of sec. C is extinguished and R lamp is lighted and train stop 11 is held in the non-stopping position by the normal retaining circuit. When the rear end of said train passes out of sec. B, train stop 30 11 assumes the stopping position and remains in said stopping position until the rear end of said train passes out of sec. D (at which time the normal clearing circuit for mechanism 13 is re-established and at the signal at the entrance to 35 sec. C the Y lamp indication is displayed instead of the R lamp) unless said train stop be put in the non-stopping position by a following train in a manner now to be described.

Assume that the first train stopped with its rear end occupying 40 sec. D. Train stop 11 is in the stopping position because the normal clearing circuit is open at contact 48 and the normal retaining circuit is open at contacts 16, 37, and 39. A following train enters sec. B and continues on to enter sec. C. 45 At the time said following train enters sec. B, contact 16 on relay 10 closes and at the time said following train enters sec. C, contact 18 on relay 9 closes and thus the circuit for the control of time delay device 26 from B, contact 16, wire 50 a17, wire 17, wire 17b, contact 14 closed with train stop 12 in the stopping position, wire 17a, contact 18, wire 19, to device 26, to O, is completed. After the lapse of the established time interval of device 26, contact 27 on device 26 55 closes to complete a circuit from B, to contact 27 (now closed), to wire 28, to wire 30, to mechanism 13, to O, whereupon train stop 11 is operated to the non-stopping position and said following train may pass.

The purpose of time delay device 26 and control circuit therefor and the control of train stop 11 by said device 26 is to provide a means whereby train stop 11 may be operated to the non-stopping position independently of the normal clearing circuit. In view of the fact that the established time interval for device 26 does not start until after contact 18 closes (due to said following train entering sec. C) and that contact 27 does not close, to complete the circuit to mechanism 13, until at the end of said 60 time interval, it is evident that said train stop 11 will remain in the stopping position until after the established time interval after said following train enters sec. C (closing of contact 18). The control of mechanism 13 by time delay device 75

26, therefore, provides means whereby the speed of a moving train is restricted to a predetermined speed while passing over distance X , while the R lamp indication is displayed at the signal 5 at the entrance to sec. C, at which time the normal clearing circuit for train stop 11 is not complete. It is manifest that the brakes of said following train will be applied by train stop 11 in the event that the established time interval for 10 device 26 has not elapsed before said train reaches said train stop 11.

Attention is here directed to the fact that device 26 may be adjusted to require any desired time interval.

15 It is to be understood further that the scope of my invention contemplates contact 14 being included in the normal retaining circuit if desired.

It is to be understood further that the scope 20 of my invention contemplates contact 14 being omitted entirely, if desired.

The object of train stop 11 is to enforce 25 obedience to a restrictive signal and this is accomplished in my invention, hereinbefore disclosed, by providing an auxiliary control means including a time delay means for operating a train stop to the non-stopping position independently of the normal operating means and thus requiring a train to pass over any distance 30 X immediately adjacent to the signal at a predetermined speed when said signal is displaying a restrictive signal, it being understood that back contact 16 on relay 18 may be omitted from the control circuit of time delay means device 26, 35 if desired, without affecting, in any way, the restriction of train movement to any predetermined speed while passing over said any distance X .

I have shown the block signal at the entrance 40 to each section as being located at the beginning of the track section and thereby retained the advantage of the block signal system functioning when the front end of a train is at the signal and the advance territory becomes unoccupied, 45 and this feature requires only that the train stop of existing train stop and signal systems be re-located when incorporating my invention, but it is to be understood that the scope of my invention includes the location of the block signal in any 50 desired location.

I desire it to be understood that applications 55 of my invention as above described but modified to provide electrical control and pneumatic operation of the train stop operating mechanism are wholly within the purview of this application.

The above rather specific description of forms 60 of my invention is given solely by way of illustration, and is not intended, in any manner whatsoever, in a limiting sense. Obviously my invention can assume many different physical 65 forms, and is susceptible of numerous modifications, and all such forms and modifications are intended to be included, in this application, as coming within the scope of the appended claims.

Having described my invention, what I claim is:

1. In an automatic train control and associated 70 block signal system, a wayside train stop having a tendency to assume its stopping position, a mechanism for operating said train stop from its stopping position to its non-stopping position, a circuit and a source of energy for operating said mechanism, said automatic block signal system controlled by a front contact on a track circuit relay, said block signal system at times controlling said mechanism to operate said train stop from

its stopping position to its non-stopping position, and auxiliary means for controlling said mechanism to operate said train stop from its stopping position to its non-stopping position, said auxiliary means including time delay means controlled 5 by a back contact on said track relay, said auxiliary means at times controlling said mechanism to operate said train stop from its stopping position to its non-stopping position to permit the movement of a train moving at less than any predetermined speed over any predetermined distance in the approach to said train stop. 10

2. The invention set forth in claim 1, with said auxiliary means controlled by a back contact on an adjacent track circuit relay in series, said train 15 stop assuming the stopping position after said adjacent track circuit becomes unoccupied by said train.

3. In an automatic train control system including 20 a train stop having a tendency to assume its stopping position located at the wayside and adapted when in the stopping position to co-act with train-carried apparatus to cause application of the train brakes, a mechanism for operating said train stop from its stopping position to its non-stopping position, a circuit including a source of energy for operating said mechanism, electrically controlled time delay means, a circuit and a source of energy for controlling said time delay means, said time delay means at times controlling 25 said mechanism operating circuit, a first track circuit located wholly in the approach to said train stop, a second track circuit located in part in the approach to said train stop and in part in advance of said train stop, said time delay means control circuit including a back contact controlled by said first track circuit and a back contact controlled by said second track circuit in series, said time delay means functioning to increase the time 30 in which said mechanism will operate said train stop from its stopping position to its non-stopping position after said train enters said second track circuit. 35

4. In an automatic train control system including 40 a train stop having a tendency to assume its stopping position located at the wayside and adapted when in the stopping position to co-act with train carried apparatus to cause application of the train brakes, a mechanism for operating said train stop from the stopping position to the 45 non-stopping position, a circuit including a source of energy for operating said mechanism, a time delay device, a circuit including a source of energy for controlling said device, a first track circuit located wholly in the approach to said 50 train stop, a second track circuit located in part in the approach to said train stop and in part in advance of said train stop, said time delay device controlling circuit including a back contact controlled by said first track circuit and a back contact controlled by said second track circuit in series, said device controlling said mechanism operating circuit. 55

5. The invention set forth in claim 4 with said 60 time delay device controlling circuit also including in series a contact closed only in the stopping position of a train stop located in the approach to the train stop of claim 4. 65

6. The invention set forth in claim 4 with a visual indication system controlled by the train stop 70 mechanism to inform the train operator as to whether said train stop is in the stopping position or in the non-stopping position.

7. In an automatic train control and associated 75 block signal system, a wayside train stop having a

tendency to assume its stopping position, a mechanism for operating said train stop from its stopping position to its non-stopping position, a circuit and a source of energy for operating said mechanism, said automatic block signal system controlled by a front contact on a track circuit relay for controlling said mechanism to operate said train stop from its stopping position to its non-stopping position, and auxiliary means for controlling said mechanism to operate said train stop from its stopping position to its non-stopping position, said auxiliary means including time delay means controlled by a back contact on said track circuit relay, said auxiliary means at times controlling said mechanism to operate said train stop from its stopping position to its non-stopping position when the associated block signal is displaying a restrictive speed signal indication.

8. The invention set forth in claim 7, with said auxiliary means for operating said train stop from its stopping position to its non-stopping position when the associated block signal is displaying a stop signal indication.

9. The invention set forth in claim 7, with said auxiliary means also controlled by a back contact on an adjacent track circuit relay in series with the back contact specified in claim 7.

10. In an automatic block signal and automatic train control system including an automatic block signal and train stop located at the wayside, said signal adapted to convey information to the operator of a train, said train stop having a tendency to assume its stopping position and adapted when in its stopping position to co-act with train carried

apparatus to cause application of the train brakes, a signal mechanism for operating said signal, a train stop mechanism for operating said train stop from its stopping position to its non-stopping position, a source of energy, a circuit for controlling said signal mechanism, a normal clearing circuit including a contact on said signal mechanism to operate said train stop from its stopping position to its non-stopping position, a normal retaining circuit including a contact on said train stop closed only in the non-stopping position of said train stop for retaining said train stop in the non-stopping position, said signal mechanism control circuit including a front contact on a track circuit relay, and auxiliary means for controlling said train stop mechanism to operate said train stop from its stopping position to its non-stopping position independently of said normal clearing circuit, said auxiliary means including a time delay means controlled by a back contact on said track circuit relay, said auxiliary means at times controlling said mechanism to operate said train stop from its stopping position to its non-stopping position to avoid causing application of the train brakes on a train moving at less than a predetermined speed in the adjacent approach to said train stop location.

11. The invention set forth in claim 10, with said auxiliary means for operating said train stop from its stopping position to its non-stopping position to avoid causing application of the train brakes on a train which stops at said train stop location.

GILBERT C. WHITNEY.
